United States Patent Office.

A. LEGRAND, AÎNÉ, OF FÉCAMP, FRANCE.

Design No. 3,077, dated June 30, 1868.

DESIGN FOR A BOTTLE.

The Schedule referred to in these Letters Patent and making part of the same.

TO ALL WHOM IT MAY CONCERN:

Be it known that I, A. LEGRAND, Aîné, of Fécamp, département de Seine-Inférieure, France, have invented a new and improved Design of Bottle for liquors or wines; and I do hereby declare that the following is a full, clear, and exact description thereof, which will enable others skilled in the art to make and use the same, reference being had to the accompanying drawing, forming a part of this specification.

The drawing represents an elevation of my new design for bottle.

This invention relates to a new design for bottles that are intended to contain French liqueur, or wine, or other beverages; and consists of the general arrangement of seals, labels, bands, and stopper, as hereinafter more fully described.

The bottle A is of suitable size, and the lower part, a, of its body, is of inverted conical form, as shown. Its neck is surrounded, below the stopper, by a band, b, made of metal or other suitable material, said band holding the lower edge of the cap c against the bottle, the cap covering the stopper. A metallic or other band, d, is laid over the cap, and extends downward in a straight, or nearly straight, direction, its lower end being covered by a seal, B, which is affixed to the body of the bottle, as is clearly shown in the drawing. Another seal, C, is affixed upon the surface of the stopper or cap. A label, E, is arranged around the neck of the bottle, above or below the band d. A circular label, D, is affixed to the lower part of the bottle, as shown.

I do not claim the designs formed upon the various seals or labels; but

I do claim as new, and desire to secure by Letters Patent—

The design for a bottle, provided with bands, seals, and labels, as set forth and shown.

The design for a bottle, provided with bands, seals, and labels, as set forth and shown.

The above specification of my invention signed by me, this 24th day of March, 1868.

A. LEGRAND, AÎNÉ.
